UNITED STATES PATENT OFFICE.

ABNER S. KIRBY, OF FREDERICKTOWN, OHIO.

CONVERTIBLE STEPLADDER.

1,323,227.

Specification of Letters Patent.

Patented Nov. 25, 1919.

Application filed June 24, 1918. Serial No. 241,577.

To all whom it may concern:

Be it known that I, ABNER S. KIRBY, a citizen of the United States, residing at Fredericktown, in the county of Knox and State of Ohio, have invented certain new and useful Improvements in Convertible Stepladders, of which the following is a specification.

This invention relates to an improved step ladder and has as its primary object to provide a device of this character which may be adjusted to form a wall ladder.

The invention has as a still further object to provide a device of the above described character employing swingingly connected ladder sections normally disposed to provide a step ladder which may be mounted from either side and wherein the said sections will be adjustable with respect to each other for varying the height of the step ladder.

A still further object of the invention is to provide an arrangement wherein the step ladder will be rigidly supported by suitable side braces against lateral tilting and wherein the said braces may be adjusted to compensate for any adjustment in the height of the step ladder.

And a still further object of the invention is to provide an arrangement wherein the ladder will be equipped with adjustable foot bars so that the ladder may readily rest upon uneven ground.

Other and incidental objects will appear as the description proceeds, and in the drawings wherein I have illustrated the preferred embodiment of the invention, and wherein similar reference characters designate corresponding parts throughout the several views:

Figure 1 is a side elevation of my improved step ladder.

Fig. 2 is an end elevation of the device,

Fig. 3 is a transverse sectional view taken on the line 3—3 of Fig. 1 and particularly illustrating the adjustable connection between the side braces of the ladder and the connecting bars between the ladder sections,

Fig. 4 is a transverse sectional view taken on the line 4—4 of Fig. 1 and looking in the direction of the arrows, this view particu-

larly showing the construction and mounting of the upper platform of the ladder,

Fig. 5 is a sectional view taken on the line 5—5 of Fig. 1, and showing the type of guide loop employed at the upper ends of the foot bars for the ladder,

Fig. 6 is a transverse sectional view taken on the line 6—6 of Fig. 1, and showing the type of guide loop employed at the lower ends of the bars, and

Fig. 7 is a fragmentary edge elevation showing the manner in which the sections of the ladder are adjusted to provide a wall ladder.

In carrying out the invention I employ co-acting ladder sections 10 and 11 respectively. The section 10 includes substantially parallel side rails 12 joined by suitable spaced steps or rounds 13. In like manner, the section 11 includes substantially parallel side rails 14 joined by suitable spaced steps or rounds 15. As particularly brought out in Fig. 2, the upper ends of the rails 14 of the section 11 are adapted to fit between the upper ends of the rails 12 of the section 10 and swingingly connecting the said sections is a transverse rod or bolt 16 extending through the upper ends of the said rails and receiving a nut 17. The ladder sections may thus be positioned in downwardly diverging relation, as shown in Fig. 1, to provide a step ladder and in this connection it is to be noted that a person may climb up either of the said sections so that the ladder may be mounted from either side. Extending between the ladder sections at a point substantially midway of the ends thereof are transverse connecting bars 18. These bars are, as particularly shown in Fig. 3, provided at their inner ends with suitable bosses lying against the outer sides of the rails 14 of the ladder section 11 and extending through these bosses as well as through the said rails is a rod 19 swingingly connecting the connecting bars with the said ladder section.

At its outer end the rod 19 is preferably equipped with a wing nut 20. The bars 18 adjacent their outer extremities are formed with longitudinally extending slots 21 and loosely fitting through these slots is a trans-

verse rod 22 which also extends through the side bars 12 of the ladder section 10 and at its outer end receives a wing nut 23 adjustable to clamp the outer ends of the said side bars against the side rails of the said ladder section for rigidly holding the ladder sections fixed with respect to each other. As particularly brought out in Fig. 3 of the drawings, the connecting bars are tapered 10 longitudinally from their outer ends toward their inner ends. Consequently, after the wing nut 23 has been once set, any tendency of the ladder sections to spread at their free extremities will cause these connecting bars 15 to wedge between the side rails 12 of the section 10, the head of the rod 22 and the wing nut 23, and thus effectually overcome such movement. At the same time this wedging action of the connecting bars will 20 tend to prevent accidental displacement of the said wing nut.

Arranged at the outer side of the ladder are vertical braces 24. These braces throughout the major portion of their length are 25 provided with longitudinally extending slots 25 through which the bolt 16 is fitted for connecting the braces at their upper ends with the apex of the ladder. Interposed between the upper ends of the said braces and 30 the side rails 12 of the ladder section 10, are suitable washers 25' upon the said bolt and, as will, of course, be readily understood, the nut 17 of the rod 16 may be readily adjusted for clamping the braces fixed against vertical movement with respect to the rod. Securing the intermediate portions of the braces to the connecting bars 18 are bolts 26, which are loosely fitted through the slots 21 of the said bars and, at their outer extremities, are freely received through the slots 25 of the braces. These bolts are preferably equipped with wing nuts 27 and interposed between the connecting bars and the braces are suitable washers 28 supporting the braces with respect to the said bars in such position that, as particularly shown in Fig. 2, the bars diverge laterally with respect to the ladder from their upper extremities toward their lower extremities. The wing 45 nuts 27 of the bolts 26 may, of course, be easily adjusted for clamping the braces in vertical position. In this connection it is to be particularly noted, as also best shown in Fig. 2, that the braces are tapered from their 50 lower extremities toward their upper extremities. Consequently, any tendency of the braces to move upwardly, under the weight of a load upon the ladder, will cause the said braces to wedge at their upper extremities between the washers 25', the head of the bolt 16 and nut 17, and, at the bars 18 between the wing nuts 27 and washers 28. Such wedging action will, of course, bind the said braces to effectually resist such vertical

movement, while, at the same time, the nut 65 17 and the wing nuts 27 will be locked against accidental displacement. The braces will thus be rigidly held to support the ladder against lateral tilting in either direction. 70

Adjustable upon the lower extremities of the side rails of the sections are a plurality of foot bars 29. These bars are, as particularly shown in Fig. 1, provided with longitudinally extending slots 30 and fitted 75 through the rails of the ladder sections to loosely engage through said slots, are pairs of spaced bolts 31 preferably equipped with wing nuts 32 operable for clamping the foot bars at adjustment upon the said rails. At 80 their upper ends the foot bars are slidably connected with the rails of the ladder sections by open guide loops 33, of the type shown in Fig. 5 of the drawings, these loops being bolted or otherwise secured to the said 85 bars. At their lower ends the foot bars are loosely received through closed guide loops 34, of the type shown in Fig. 6 of the drawings, these guide loops being bolted or otherwise secured to the rails of the ladder sections. The guide loops 33 and 34 are thus 90 adapted to slidably support the foot bars upon the rails of the ladder sections for movement to project below the lower ends thereof and, as will be readily understood, the several foot bars may, when it is desired to rest the ladder upon uneven ground, be readily adjusted for supporting the ladder in an erect position. The foot bars are, as particularly brought out in Fig. 2, also tapered longitudinally from their lower ends 95 toward their upper ends so that any tendency of the said rods to shift upwardly upon the rails of the ladder sections, under the weight of a load upon the ladder, will act to 100 wedge the said bars between the said rails and the wing nuts 32 of the bolts 31 and consequently bind the said bars in fixed position. At the same time, such wedging action 105 will also tend to lock the wing nuts 32 against accidental displacement. As will be seen, these foot bars and guide loops therefore, while being particularly designed for use in connection with the present invention, are nevertheless adapted for general application and may accordingly be applied to 110 and effectively employed upon various types of ladders already in service. 115

Mounted upon the uppermost of the rounds 13 and 15 of the ladder sections is a 120 platform 35. This platform includes spaced upper and lower members 36 supported in parallel relation by a suitable spacing block 37 interposed between said members, as particularly shown in Fig. 4, at a point substantially midway between the ends thereof. Connecting the said members and extending through the block are bolts 38. The

uppermost of the rounds 13 and 15 of the ladder sections are slidably received between the extremities of the members 36 at opposite sides of the block 37. Consequently, while the said platform may be shifted upon the said rounds transversely with respect to the ladder, the block 37 will, nevertheless, hold the said platform against displacement. This provides an arrangement whereby should the platform be found in the way when mounting the ladder at one side thereof, the said platform may simply be shifted to the opposite side. Mounted upon the outer extremities of the connecting bars 18 is a second platform 39. This platform is detachably connected with the bars by loops 40 loosely receiving the terminal portion of the said bars and is held against displacement by pins 41 removably fitting in suitable openings in the upper edge of the bars. Preferably, the pins 41 are connected with the platform, as best shown in Figs. 1 and 2, by suitable flexible elements to prevent accidental loss of the said pins. Since the platform 39 is somewhat lower than the platform 35, it will be seen that I have provided an arrangement whereby a workman may stand upon the lower platform while a bucket or other utensil of the workman may be rested upon the upper platform in convenient position.

As will now be seen in view of the preceding description, by releasing the wing nut 20 of the rod 19, the wing nut 23 of the rod 22, the wing nuts 27 of the bolts 26, and the wing nut 17 of the bolt 16, the ladder sections 10 and 11 may be spread at their lower extremities for adjusting the height of the ladder, when the said nuts may again be tightened up for clamping the several parts in adjusted position. In this way the height of the ladder may be easily varied. When the ladder is thus adjusted, the platform 39 is, of course, first removed by displacing the pins 41 and should the ladder sections be spread to such extent that the members 36 of the platform 35 will not reach between the uppermost of the rounds of the ladder sections, this latter platform may also be removed.

In order to form the device into a wall ladder, the connecting bars 18 and braces 24 are removed as are also the platforms 35 and 39. The bolt 16 is then removed when the ladder sections 10 and 11 are disposed in alinement, as shown in Fig. 7, with the inner ends of the side rails 14 of the section 11 abutting the uppermost round 13 of the section 10. In this position of the said sections the bolt openings adjacent the upper ends of the side rails of the section 10 will register with similar bolt openings 42 formed in the side rails of the section 11 adjacent the uppermost round 15 of the said

section. The bolt 16 is accordingly fitted through these registering bolt openings for again rigidly connecting the ladder sections to form the wall ladder, and in order to prevent inward bowing of the ladder at the meeting ends of the sections, the upper terminals of the side rails of the section 11 are formed with longitudinally extending lugs 43 adapted to engage over the uppermost round 13 of the ladder section 10 for rigidly supporting the inner extremities of the sections against inward movement relative to each other. The foot bars at the lower end of the section 10 may, of course, be readily adjusted to support the wall ladder upon uneven ground and by employing the pairs of bolts 31 for holding the said bars in adjusted position liability of possible slipping of the said bars will be effectually overcome.

It will, therefore, be seen that I have provided a particularly efficient type of ladder and a ladder which may not only be used as an ordinary step ladder but may also be easily adjusted to form a wall ladder. Furthermore, when used as a step ladder the device will be rigidly supported against lateral tilting movement and may by proper adjustment of the foot bars thereof also always be arranged in an upright position without regard to any unevenness in the surface upon which the ladder is rested.

Having thus described the invention, what is claimed as new is:

1. A device of the character described including coacting ladder sections, means swingingly connecting said sections, a cross connection between the sections, and lateral brace means for the sections arranged at opposite sides thereof and held by said connecting means, said brace means being adjustable vertically upon said connecting means.

2. A device of the character described including swingingly connected ladder sections, adjustable cross connecting means between the sections, and lateral brace means connected with the upper end portions of the sections at opposite sides thereof and engaging with the adjustable cross connecting means between the sections.

3. A device of the character described including coacting swingingly connected ladder sections, connecting bars between the sections swingingly connected to one of the sections, and means adjustably connecting the free end portions of said bars with the other of the sections, the bars being longitudinally tapered to coact with said last mentioned section for holding the bars wedged against longitudinal movement with respect thereto.

4. A device of the character described including coacting ladder sections connected at their upper ends, cross connecting means be-

tween the sections, lateral brace means connected with the upper ends of the sections at opposite sides thereof, and means clamping the lateral brace means and cross connecting means together.

5. A device of the character described including coacting swingingly connected ladder sections, adjustable cross connecting means between the sections, lateral brace means arranged at opposite sides of the sections, and means adjustably connecting said

lateral brace means with said cross connecting means.

6. A device of the character described including coacting ladder sections, cross connecting means between the sections, and lateral brace means arranged at opposite sides of the sections and clamped intermediate of their ends against lateral movement with respect to the sections.
